JOHANNES KJEKSTAD, OF BROOKLYN, NEW YORK

CONTAINER AND THE LIKE AND BRACING FOR THE SAME

Refiled for abandoned application Serial No. 625,988, filed March 19, 1923. This application filed February 9, 1927. Serial No. 167,046.

In metal containers where the shell is entirely or partly made up of flat surfaces or plates and must withstand internal pressure either under working conditions or for testing purposes, the common practice heretofore has been either to dish the surfaces where possible, as in cylindrical tanks, or where the containers are hexahedrons, the flat sides are generally braced on the inside with angles or channels riveted to the shell, with the angles or channels tied together by tie-rods or braces. This construction, however, necessitates the use of a comparatively large amount of material for bracing and often necessitates an increase in the thickness of the shell, to give sufficient stiffness thereto with a comparatively wide spacing of braces, this wide spacing being necessary to give accessibility to all parts of the tank internally during erection and while in operation for cleaning purposes or repairs.

An object of the invention is to provide a tank or container with improved bracing or reinforcement so that it will have a maximum rigidity and resistance to internal pressure, with a minimum reduction in the capacity of the tank caused by the insertion of the bracing or reinforcing, and with a minimum of metal necessary for the construction of the tank and bracing which is adapted to carry a substantial top load such as a covering of earth, without deformation, and to resist an internal pressure in excess of the unit weight of top load; with which ready access may be had to all parts of the interior of the tank during both erection and operation; and which will be relatively inexpensive. Other objects and advantages will be apparent from the following description of an embodiment of the invention and the novel features will be particularly pointed out hereinafter in claim.

In the accompanying drawing:

Fig. 1 is a plan of a tank constructed in accordance with the invention;

Fig. 2 is an end elevation of the same;

Fig. 3 is a sectional elevation on a larger scale of a portion of the tank at one of the corners;

Fig. 4 is a fragmentary sectional eleva-

tion of a tank having the improved reinforcement or bracing, which is applied thereto in a slightly different manner; and

Fig. 5 is a similar view showing a still further mode of attaching the bracing to the tank walls.

Referring particularly to Figures 1 to 3, the tank as illustrated, has the shape of a hexahedron, and its walls are designated by the reference characters *a*, *b*, *c*, *d*, *e*, *f*. The opposite walls of the container are connected by tie-rods 1 which are spaced from one another and secured at their ends to the walls of the tank by welding. In this embodiment of the invention the tie-rods have a length substantially equal to the distance between the walls which they connect, and the rods at their ends are welded, by a suitable welding fillet 2, to the inner faces of the walls which they connect. The tie-rods connecting the lateral walls of the tanks are preferably arranged in horizontal layers or groups disposed at different elevations, as illustrated in Fig. 2. The rods of each group which extend between any two pair of opposite walls are preferably in engagement with and welded to the rods in the same group which connect the other two opposite lateral walls of the container. The tie-rods connecting the top and bottom walls of the container are preferably disposed along the corners formed by the crossing rods in each group of horizontally disposed tie-rods, and at each corner the vertical tie-rods are secured or tied to the horizontally arranged rods in any suitable manner, preferably by tack welding. The corner edges of the container may be reinforced by suitable angle members 3 which are welded, as at 4, to the intersecting walls. The intersecting walls at each edge may also be welded together as at 5.

The vertical rods are thus welded to the top and bottom walls of the container and are adapted to carry stresses both in tension and in compression. Internal pressure from the contents of the tank produces forces in tension, and the tie-rods, vertical as well as horizontal, then have no tendency to bend or buckle. If the tank is buried in the ground, as is frequently the case, with an overburden

of earth on the top, the tie-rods may also be put into compression. Under these conditions the top wall may be quite heavily loaded. With the tank filled, sufficient internal pressure may be produced to support the overburden. However, when the tank is empty, the whole of the top load becomes effective to buckle the top wall. The weight of the overburden is then supported, in the construction of my invention, by the vertical tie-rods. These rods are, however, relatively slender, and alone would be insufficient to carry the compression stresses produced by the overburden, since they would bend and twist from under the load. This tendency is resisted, and the vertical tie-rods are enabled to carry the load of the overburden by the strengthening effect of the transverse tie-rods which support the vertical tie-rods at frequent intervals.

In Figure 4 a different manner of securing the tie-rods to the walls is illustrated. In this embodiment the opposite walls *g* and *h* of the tank are connected by one or more tie-rods 8, similar to the rods 1 and 6 but which instead pass through apertures in the connected walls, the outer ends of the tie-rods being welded to the outer faces of the connected walls, as by a fillet 9. In Figure 5 a slightly different manner of securing the tie-rods to the walls is illustrated. In this embodiment one or more rods 10 which connect the walls *i* and *j* of the tank extend through the walls and have their projecting ends threaded and carrying nuts 11. After the nuts are adjusted into contact with the outer faces of the walls, they may be welded to the outer face of the connected walls so as to seal the openings through which the rods pass.

It will be observed that with this manner of bracing the tank against internal pressure, channel angle and flat plate members heretofore commonly used have been replaced by tie-rods of uniform cross-section which occupy less space in the container and which can be so arranged relatively to one another that the space between them will be as large as possible, so as to enable one to pass between them while erecting, cleaning or repairing the tanks. When the tie-rods are welded to the walls of the container, the forces thereon will be tensile and not shearing, and each tie-rod reinforces and stiffens the other tie-rods with which it contacts or to which it is secured. A tank with this type of bracing will have a maximum rigidity and will withstand exceptionally high internal and external pressures with a minimum amount of steel required for the construction of the tank and bracing.

It will be obvious that various changes in the details and arrangements of parts herein described and illustrated for the purpose of explaining the nature of the invention, may be made by those skilled in the art within

the principle and scope of the invention as expressed in the appended claim.

I claim as my invention:

In a device having lateral, top and bottom enclosing walls, a series of tie-rods arranged in horizontal groups at different levels, each group comprising two angularly disposed rows of rods anchored to opposed walls and connected at their points of crossing to form an integral truss construction, and a series of vertical tie-rods anchored to the top and bottom walls with each rod disposed immediately adjacent the points of crossing of two rods in several of the horizontal groups and connected to the two rods at each of such points of crossing, whereby the rods are resistant to both internal and external stresses without deformation.

In witness whereof, I hereunto subscribe my signature.

JOHANNES KJEKSTAD.
